DEVICE AND METHOD FOR HANDLING
EGGS

Roy C. Potts, Takoma Park, Washington, D. C.

Application January 24, 1938, Serial No. 186,677

3 Claims. (Cl. 226—18)

(Granted under the act of March 3, 1883, as
amended April 30, 1928; 370 O. G. 757)

This application is made under the act of March 3, 1883, as amended by the act of April 30, 1928, and the invention herein described and claimed, if patented, may be manufactured and used by or for the Government of the United States for governmental purposes without the payment to me of any royalty thereon.

My invention relates to a device and a method for loading and unloading eggs from boxes, cartons, cases, or other containers.

In present commercial practice eggs are frequently packed in standard thirty-dozen cases constructed with two compartments, each compartment holding fifteen dozen eggs. The individual eggs are packed in cellular forms, such as standard honeycomb fillers with supporting flats; and in filler-flats such as the "Kys Filler-Flat" (see U. S. Patent No. 1,970,436). When eggs are thus packed in a case or carton, it was necessary heretofore to unpack them either by taking one or two handfuls at a time or one layer at a time from the case. This involves a great deal of labor and time and is unsatisfactory from an industrial point of view because after the eggs are unpacked in such a manner, they are not in convenient form to handle in large quantities.

An object of my invention is to provide a device and a method for packing and unpacking eggs which will considerably reduce the labor and time necessary to handle eggs in large quantities.

Another object of my invention is to provide a device which is simple to manufacture, easy to operate, and which, in addition to being useful in the packing and unpacking of eggs, is also useful in handling eggs prearranged in cellular forms after or before they are packed in boxes or cartons.

A further object of this invention is to provide such a device and method for handling eggs which can be utilized in connection with a case openable at both top and bottom, such as the collapsible case disclosed in U. S. Patents Nos. 1,850,183 and 2,057,852.

The following description, together with the accompanying drawing, will disclose this invention more fully and further objects and advantages thereof will be apparent.

In the drawing:

Figure 1 is a perspective view of my invention in one of its forms.

Figure 2 is a perspective view of my invention in an alternative (hinged) form.

Figure 3 shows the alternative form of my invention collapsed.

Figure 4 is a perspective view showing how my invention may be utilized in packing eggs in a case or removing them therefrom.

Referring with more particularity to the drawing in which like numerals designate like parts, the form of my invention shown in Figure 1 consists of a base section 4 and two vertical side sections 5, 5, all of which may be fabricated of stiff wire or any other suitable material. In this form of my invention, the sides 5, 5 are substantially in a fixed position with respect to the base section 4. In the alternative form of my invention, as shown in Figures 2 and 3, the vertical sides 5a and 5b are hinged to the base section 4a by means of coil springs 8a and 8b so that the entire device can be folded flat. The coil springs 8a and 8b are integral with the sides 5a and 5b and the base section 4a, the springs on one side being coiled in a direction opposite to those on the other side. As shown in Figures 2 and 3, the springs 8a are coiled so that the side 5a is on the outside, while the side 5b is on the inside of the springs 8b. This constitutes the side 5b narrower than the side 5a, enabling the device to be folded, as shown in Figure 3. A handle 6, which may be formed of the same material as the other parts of the device, is adapted to be removably mounted between the top of the sides 5, 5 and to accomplish this purpose the handle is provided with open loops 7, 7 curved inward and diametrically opposite. The open ends of these loops are just sufficient to allow the upper portions of the sides 5, 5 to enter the loops. The normal flexure of these sides 5, 5 enables them to be forced in and out of the loops. The normal position assumed by the sides 5, 5 keeps them from slipping out of the loops in the form shown in Figure 1. In the alternative form of this invention shown in Figures 2 and 3, hinged hooks 9 hold the device in a folded position.

In the ordinary egg case having only one side openable, this device may be used in several ways. For example, it may be inserted in the case, and the eggs packed therein with the cellular forms. Where the case contains two standard size compartments, two of these devices may be utilized, one for each compartment. After the eggs are thus packed the case may be closed, sealed, and shipped in the usual manner. Whenever it is desired to unpack these eggs, the case is opened and all the eggs in each compartment are simply removed at one time by means

- of the device. (While the device may be utilized with the handle 6, the use of this handle is not indispensable and the eggs may be removed or handled with two hands by merely grasping the sides 5, 5.) With the eggs in this position, they may be transferred from place to place very conveniently with the device, and, as a matter of fact, may be placed on display in such places as retail stores, and the like.
- 10 Instead of packing the eggs directly into a case or carton, or a compartment thereof, they may be prearranged in cellular forms, such as the filler-flats 10 in Figure 4, on the device and then placed into the case together with and by means of the device, as illustrated in Figure 4. Where it is desired to remove the device from the case after packing, the case can be inverted over the prearranged eggs on the device, then reverted, and the device removed. Where a case 20 openable at both its top and bottom is utilized, the eggs together with and by means of the device may be inserted in the case through its top which is then closed, the case inverted, and the frame removed by opening the bottom of the case, which can afterwards be closed in the usual manner.

Where this device has not been incorporated in a packed case of eggs, the following method may be used to unpack the eggs: The case is opened 30 and the device, in an inverted position, is inserted into a compartment of the packed eggs. Where a case contains two compartments, such as the case 11 shown in Figure 4, two of such devices can be utilized, one for each compartment. After the device is inserted, the case is inverted. With the open side of the case and the base of the device resting on a floor or table, the case can be lifted off the eggs. The handles 6 can then be attached to the device and each 40 of the units of packed eggs handled as hereinabove mentioned. This last-mentioned method, however, makes it necessary to use considerable care while inverting the case with the side open. For the sake of safety, it would be necessary to 45 place a board or similar object across the open side to keep the device and the eggs from falling out while the case is being inverted. However, where a case is utilized having both its top and bottom openable, this device may be inserted in

the compartments as above described at the bottom of the case, which is then simply closed, inverted, opened at its top, and the eggs removed as above-described by means of the device.

Where collapsible cases are used, such as the ones disclosed in U. S. Patents Nos. 1,850,183 and 2,057,852, it may be desired to utilize that form of this invention shown in Figures 2 and 3 so that both the case and the device may be folded together for the purpose of conserving space after the eggs are removed. However, it is to be understood that the use of that form of my invention shown in Figures 2 and 3 is not restricted to collapsible cases and that either form of my invention may be used interchangeably 15 with any form of carton, box or case, or for any other purpose.

Having thus described my invention, I claim:

1. A collapsible frame for handling units of eggs prearranged in cellular forms, said frame consisting of a base section, two side sections yieldably hinged to said base section, constituting said side sections foldable into said base section, means for holding said side sections in a foldable position against the yieldable action of 25 said side sections, and a handle adapted to be removably disposed across said side sections.

2. A collapsible device for handling units of eggs prearranged in cellular forms, said device consisting of a frame having a horizontal base section, a plurality of side sections hinged to and collapsible on the said base section, yieldable means for normally holding said side sections in a vertical position, means for holding said side sections in a collapsed form against the action 35 of said yieldable means, and a handle adapted to be removably mounted horizontally between the top of two side sections.

3. A collapsible device for handling units of eggs prearranged in cellular forms, said device 40 comprising a frame having a horizontal base section, a plurality of side sections hinged to said base section, said side sections being hinged so that they are collapsible on said base section, yieldable means for normally holding said side sections in a vertical position, and means for holding said side sections in a collapsed form against the action of said yieldable means.

ROY C. POTTS.
